US00D901170S

(12) United States Design Patent (10) Patent No.: US D901,170 S
(45) Date of Patent: * Nov. 10, 2020

(54) BAG

(71) Applicant: Valentino S.p.A., Milan (IT)

(72) Inventor: Stefano Sassi, Milan (IT)

() Term: 15 Years

(21) Appl. No.: 35/507,549

(22) Filed: Jun. 6, 2019

(80) Hague Agreement Data

Int. Filing Date: Jun. 6, 2019

Int. Reg. No.: DM/203468

Int. Reg. Date: Jun. 6, 2019

Int. Reg. Pub. Date: Oct. 25, 2019

(51) LOC (12) Cl. 03-01

(52) U.S. Cl.

USPC D3/232; D3/243

(58) Field of Classification Search

USPC D3/201, 216, 232–233, 240–243,
D3/245–247, 299, 303, 318

CPC A45C 1/024; A45C 3/06

See application file for complete search history.
